UNITED STATES PATENT OFFICE.

JAMES B. EASTES, OF KONAWA, OKLAHOMA.

CRANKING DEVICE.

1,071,990.

Specification of Letters Patent.

Patented Sept. 2, 1913.

Application filed June 23, 1911. Serial No. 634,934.

To all whom it may concern:

Be it known that I, JAMES B. EASTES, citizen of the United States, residing at Konawa, in the county of Seminole and 5 State of Oklahoma, have invented certain new and useful Improvements in Cranking Devices, of which the following is a specification.

This invention relates to cranking devices 10 for explosive engines and is designed more particularly for use upon motor driven vehicles and aims, primarily to provide means whereby the engine shaft may be cranked without the necessity of the operator of the 15 engine leaving his seat.

The invention aims further to provide a cranking mechanism so constructed that the initial operation of its actuating means will serve to move the cranking shaft into clutch 20 with the engine shaft, and subsequent actuation of such means will serve to rotate the cranking shaft.

Another aim of the invention is to so construct the cranking mechanism that should 25 the engine back-fire the cranking shaft will be entirely free to rotate and no inconvenience will be caused the operator of the machine.

A further aim of the invention is to so 30 construct the cranking mechanism that it may be readily adjusted for use in connection with engines which are more or less difficult to crank.

For a full understanding of the invention 35 reference is to be had to the following description and accompanying drawing, in which:—

Figure 1 is a plan view of the mechanism mounted upon the frame of a motor driven vehicle. Fig. 2 is a vertical transverse sectional view on the line 2—2 of Fig. 1. Fig. 3 is a longitudinal sectional view on the line 3—3 of Fig. 1. Fig. 4 is a rear elevation, in detail, of a portion of the 40 mechanism. Fig. 5 is a vertical longitudinal sectional view on the line 5—5 of Fig. 4. Fig. 6 is a detail view partly in elevation and partly in section illustrating the support 45 for the mechanism shown in Figs. 4 and 5.

Corresponding and like parts are referred 50 to in the following description and indicated in all the views of the accompanying drawings by the same reference characters.

In the drawings, only the forepart of the 55 frame of the vehicle is illustrated and of this portion of the frame the chassis beams are

indicated by the numeral 1 and the front axle by the numeral 2.

3 indicates the usual apron which depends from the front of the radiator and which 60 serves as a support for the usual cranking shaft.

The engine shaft is indicated by the numeral 4 and is provided at its forward end with a clutch head 5. In place of the cranking shaft usually provided there is, in the present instance, provided a cranking shaft 6 which is rotatably and slidably fitted through the apron 3 and is provided at its rear end, with a clutch head 7 designed to 70 coöperate with the clutch head 5 when the cranking shaft is shifted rearwardly. The shaft 6 is threaded as indicated by the numeral 7' and is preferably headed at its forward end as at 8.

A collar 9, interiorly threaded as at 10 is fitted upon the threaded portion of the cranking shaft 6 and is designed to be moved longitudinally upon this shaft and, during such movement is to be held relatively fixed 8 whereby to rotate the said cranking shaft and impart corresponding movement to the engine shaft 4. A collar 11 is fitted upon the collar 9 and the collar 9 is free to rotate within the collar 11 under conditions which 85 will be presently explained. The collar 9 is formed, peripherally with a number of notches 12 and a number of pawls 13 are pivoted as at 14 within a recessed side of the collar 11 and engage their free ends in the 90 notches 12.

Springs 15 are engaged at their ends over studs 16 and 17 upon the wall of the recess in the collar 11 and each pawl 13 respectively, it being understood that these springs 95 serve to yieldably hold the pawls in engagement in the said notches.

A collar 18 is fitted upon the collar 11 and the said collar 11 is rotatable within the collar 18 independently thereof, under conditions which will be presently explained in connection with the description of the operation of the device. The collar 11 is formed peripherally with a number of notches 19 and pawls 20 are pivoted upon 100 the periphery of the collar 18 and project through openings 21 therein and seat at their free ends in the notches 19. A leaf-spring 22 is provided for holding each pawl 20 in 105 yieldable engagement in its respective notch 19 and each of these leaf-springs is formed with a slot 23 through which a set-screw 24 110

is engaged, the set-screw being threaded into the collar 18 and serving to hold the spring in place, its free end bearing against the shank of the respective pawl 20, in the manner illustrated in Fig. 4 of the drawings. It will be readily understood at this point that by loosening the set-screw 24 and sliding the springs 22 in the direction of the extent of their slots 23, and then tightening the set-screws; the tension of the springs may be adjusted so that a greater or less force will be required to be exerted upon the collar 11 to rotate the same.

A lever-arm 25 is pivoted at one end as at 15 26 to a bracket 27 secured to one of the chassis-beams 1, preferably the left-hand one, and this arm is formed at a point between its ends with an annular head 28 through which are threaded, at diametrically opposite points, screws 29 having their outer ends fitting in apertures 30 in ears 31 which are formed or secured upon one face of the collar 18. By so connecting the lever-arm 25 with the collar 18, this collar together with the collars 9 and 11 may move along the cranking shaft without danger of binding thereon. A rod 32 is connected to the end of the lever-arm 25 opposite its pivoted end and to a foot-lever 33 carried in 30 the front of the car. The connection between the lever-arm 25 and foot-lever 33 is such that when the foot-lever is rocked forwardly, the arm will be swung rearwardly upon its pivot and will move the collars 9, 35 11 and 18 along the cranking shaft. A spring 34 is fitted upon the threaded portion of the shaft and bears at its forward end against the collar 9 and at its rear end against a collar 35 which is fixed upon the 40 said cranking shaft and this spring serves to yieldably hold the collar 9 against rearward movement upon the said shaft and also serves to shift the collar forwardly after it has been moved rearwardly to rotate the 45 shaft, and is released. A spring 36 is also arranged upon the cranking shaft and bears at its forward end against the said collar 35 and at its rear end against the apron 3 through which the shaft is mounted and this 50 spring serves to yieldably hold the cranking shaft at the forward limit of its movement and out of clutch with the engine shaft.

In operating the device the foot-lever is 55 depressed, whereupon the arm 25 will be swung rearwardly forcing the collar 9 in a corresponding direction along the threaded portion of the cranking shaft. The pawls 13 serve to hold this collar against backward rotation and the pawls 20 serve to yieldably 60 hold the collar 11 against rotation to the left in Fig. 4 of the drawing, the spring 22 being so adjusted that the collars 9 and 11 will be held relatively fixed so that the cranking shaft will be rotated. The spring 65 36 is of less strength than the spring 34, and

as a consequence the initial backward movement of the lever arm 25 will result in the cranking shaft being shifted rearwardly to bring its clutch head 7 into engagement with the clutch head 5 at the forward end of the engine shaft. Further movement of the lever arm in the direction stated, will however, result in the collar 9 and the related collars 11 and 18 being moved rearwardly along the cranking shaft to rotate the same in the manner above described. Should the engine 75 back-fire, the rotary movement imparted to the cranking shaft will be transmitted to the collars 9 and 11 and these collars will be rotated in unison, the holding force of the 80 pawls 20 being overcome.

When the engine has been cranked, the foot-lever is relieved of pressure and the spring 34 will automatically return the collar 9 to its original position, the collar, however, rotating upon the shaft in a direction 85 toward the right in Fig. 4 of the drawings, as it moves forwardly therealong.

The forward end of the cranking shaft 6 projects beyond the end 28 of the lever arm 25 and has its projecting portion squared as at 37 for the engagement therewith of an ordinary cranking handle by means of which the engine may be manually cranked, if desired. By adapting the device to be manually cranked by the crank handle, the motor may be cranked when it is being repaired, without the necessity of entering the car.

Having thus described the invention what is claimed as new is:—

1. The combination with an engine shaft, of a threaded cranking shaft arranged to be clutched therewith, a threaded member movable along the cranking shaft and arranged by such movement to rotate the said cranking shaft, means yieldably holding the member against rotation in one direction, and means for moving the said member along the cranking shaft.

2. The combination with an engine shaft, of a threaded cranking shaft arranged to be clutched therewith, a threaded member movable along the cranking shaft and arranged by such movement to rotate the said shaft, a member fitted upon the first mentioned member and movable therewith, a pawl carried by the last mentioned member and co-operating with the first mentioned member whereby to hold the same against rotation in one direction, means yieldably holding the last mentioned member against rotation, and means for moving the threaded member along the cranking shaft.

3. The combination with an engine shaft, of a threaded cranking shaft arranged to be clutched therewith, a threaded collar upon the cranking shaft arranged for movement therealong and, by such movement to rotate the said cranking shaft, a collar fitted upon the first mentioned collar, a pawl carried by

one of said collars and coöperating with the other collar whereby to hold the first mentioned collar against rotation independently of the second mentioned collar in one direction, a spring pressed pawl coöperating with the last mentioned collar and yieldably holding the same against rotation in one direction, and means for moving the said collars along the cranking shaft.

10 4. The combination with an engine shaft, of a threaded cranking shaft arranged to be clutched therewith, a threaded collar upon the cranking shaft movable therealong and arranged by such movement to rotate the said cranking shaft, a collar fitted upon the first mentioned collar, the first mentioned collar being rotatable independently of the second mentioned collar in one direction, means holding the first mentioned collar against rotation independently of the second mentioned collar in the opposite direction, a collar within which the second mentioned collar is rotatably fitted, yieldable means upon the last mentioned collar coöperating 20 with the second mentioned collar to yieldably hold the second collar against rotation within the last mentioned collar, and means connected with the last mentioned collar for moving the same and the first and second mentioned collars lengthwise of the cranking shaft.

5. The combination with an engine shaft, of a threaded cranking shaft arranged to be clutched therewith, a threaded collar movable along the cranking shaft and arranged by such movement to rotate the said cranking shaft, a collar within which the first mentioned collar is rotatable, means for clutching the first and second mentioned collars to hold the first mentioned collar against rotation in one direction, independently of the second mentioned collar, a collar within

which the second mentioned collar is rotatable, the second mentioned collar being formed with a peripherally located notch, a pawl carried by the last mentioned collar and engaging in the notch in the periphery of the second mentioned collar, a spring bearing on the pawl, means for adjusting the tension of the spring, and means connected with the last mentioned collar for moving the same and the first and second mentioned collars along the cranking shaft.

6. The combination with an engine shaft, of a threaded cranking shaft arranged to be clutched therewith, a threaded collar on the cranking shaft movable therealong and arranged by such movement to rotate the said cranking shaft, a collar within which the first mentioned collar is rotatable, means holding the first mentioned collar against rotation independently of the second mentioned collar in one direction, means yieldably holding the second mentioned collar against rotation in one direction, a collar fixed upon the cranking shaft, the said cranking shaft being movable longitudinally into clutch with the engine shaft, a spring upon the cranking shaft bearing against the first and last mentioned collars and yieldably holding the first mentioned collar against movement along the said cranking shaft, and a spring upon the cranking shaft bearing against the last mentioned collar and yieldably holding the cranking shaft against movement into clutch with the engine shaft.

In testimony whereof, I affix my signature in presence of two witnesses.
